UNITED STATES PATENT OFFICE

REMI J. GITS, OF CHICAGO, ILLINOIS

MULTIPLE OILER

Application filed April 4, 1927. Serial No. 180,871.

The main objects of this invention are to provide an improved type of multiple oiler, which is simple in construction and efficient in operation; to provide a multiple oiler in which all the oil discharge nozzles are opened in unison by a unitary member; and to provide an oiler in which the flow of oil can be regulated by adjustment of a wick which is located in each of the oil discharge nozzles.

10 An illustrative embodiment of this invention is shown in the accompanying drawings, in which:—

Fig. 1 is a top plan view of the oiler, with a portion of the cover plate broken away to 15 show the interior construction.

Fig. 2 is a side elevation of the same, with a part thereof shown in vertical section.

In the construction shown in the drawings, a reservoir 1 is provided for containing 20 a supply of lubricating oil. Said reservoir is constructed so as to have integral side and end walls 2 and 3 respectively, and a floor 4. The floor of the reservoir is provided with a plurality of threaded openings, in which are 25 screwed a plurality of tubes 5 which extend upwardly from the floor of the reservoir to a point closely adjacent the top of the reservoir and above the normal level of the lubricating oil therein.

30 The top edges of the upstanding tubes 5 are each provided with notches 6 for receiving a wick 7, one end of which is helically wound around the tube 5, and extends down into the oil of the reservoir and the 35 other end of which passes through the notch 6 and extends down into the interior of the tube 5.

The wick 7 has a metallic core 8, and regulation of the flow of oil from the reservoir is 40 secured by burning or otherwise removing the wicking from the metallic core for a certain distance at the end of the wick which extends down within the tube 5. The further up the core this wicking is removed the slower will be the flow of oil, and the further down the wicking extends the faster will be the flow of oil.

The lower end of each of the tubes 5 is provided with an oil discharge opening, and has 45 a downwardly facing valve seat which coacts

with a valve 10 carried on the lower end of a valve stem 11. The valve stem 11 is housed concentrically within the tube 5, and the upper end extends above the top end of the tube 5. A cap 12 is secured to the top end of each 55 of the valve stems 11 and provides a bearing seat for a coiled compression spring 13, which bears between the under side of the cap and the top side of an upwardly facing cup 14, which is concentrically disposed and 60 carried upon the top end of the tube 5.

Means are provided for bearing down on all of the caps 12 in unison, thereby forcing the valves 10 downwardly from their respective valve seats so as to permit the flow of 65 oil, and comprises a plate 15 carried on the under side of the detachable reservoir cover 16, which is secured to the reservoir by suitable means, such as screws 17. The plate 15 is provided with a pair of upstanding studs 18, which extend upwardly through apertures formed in the cover plate 16. Means are provided for engaging the studs 18 and forcing them downwardly so as to cause the plate 15 to engage and force down the caps 12 to open 70 the valves 10, and comprise a pair of cam levers 20, pivotally mounted on upstanding lugs 21, formed on the top surface of the 75 reservoir cover plate 16.

Means are provided for filling the reservoir 80 with lubricating oil, and comprise an oil filler cup having a body part 25, mounted on one end of the reservoir and communicating therewith. The cup 25 carries a longitudinally disposed pivot pin 26, upon which is hingedly mounted a cover 27. A coil torsion spring 28 is wound about the pin 26. One end of the spring bears against the body part 25, and the other end of the spring is disposed in a notch 29 formed in the cover 27 adjacent the point of hinged connection, and bears against the cover so as to normally hold it in closed position on the cup 25.

85 The notch 29 for receiving one end of the torsion spring 28 retains the end of the spring in position at all times, and permits the upper end thereof to be filed or ground off flush with the top surface of the cover so that it 90 will not catch on waste or wiping rags used to clean the oiler.

The opposite end of the oiler carries the usual sight gage glass 35, for visually showing the height of the oil in the reservoir, and communication between the sight glass 35 and reservoir is provided by an opening 36. A plug 37 is threaded into the top end of the gage frame for retaining the sight glass therein, and said plug is provided with a passageway 38. This passageway communicates with the interior of the glass 35 and the atmosphere for venting the air in the gage so that the oil can flow into the glass 35.

In the operation of the device, the reservoir is filled by raising the cover 27 and pouring oil into the cup 25, which communicates with the interior of the reservoir. The wicks 7 conduct the oil from the reservoir upwardly and then downwardly into the interior of the tubes 5 by capillary attraction aided by a siphoning action after the flow has once been established. When it is desired to have the oil flow through the various discharge nozzles or openings, the cam levers 20 are turned to an upright position, thus forcing down the studs 18 carried on plate 15, thus causing the plate 15 to contact in unison with all of the caps 12 which are mounted on the top ends of the valve stems. Downward movement of the caps and valve stems moves all of the valves 10 downwardly from their seats and thus permits the oil to flow through the discharge nozzles.

When it is desired to shut off the flow of oil, the manually operable levers 20 are returned to their horizontal position, and the springs 13 of the respective oiler units carry the plate 15 upwardly and thus close each of the valves 10 individually on their respective valve seats.

Although but one specific embodiment of this invention has been herein shown and described, it will be understood that numerous details of the construction shown may be altered or omitted without departing from the spirit of this invention as defined by the following claims.

I claim:

1. A multiple oiler comprising a reservoir adapted to contain oil, a plurality of upstanding tubular members mounted on the floor of said reservoir and communicating with the interior thereof, the lower end of each of said members being provided with an oil discharge opening, a valve for each of said openings, a valve stem housed in each of said tubular members for controlling the respective valve of each discharge opening, individual resilient means for normally holding each of said valves in a closed position, and a manually operable unitary member contacting with all of said valve stems for opening all of said valves in unison.

2. An oiler comprising a reservoir adapted to contain oil, an upstanding tubular mem-

ber mounted in the floor of said reservoir and communicating with the interior thereof, the lower end of said tubular member being provided with a discharge opening, a valve for controlling the flow of oil through said opening, a valve stem concentrically mounted within said tubular member for controlling said valve, the upper end of said valve stem projecting above the top end of said tubular member, a cap mounted on the top end of said valve stem, resilient compression means bearing between the under side of said cap and the top end of said tubular member for normally holding said valve in a closed position, a manually operable cam lever mounted on said reservoir for pressing down on said cap to open said discharge valve, and a wick disposed in said reservoir and partially within said tubular member for conducting oil from said reservoir to said discharge opening.

3. A multiple oiler comprising a reservoir adapted to contain oil having a floor, side walls, and end walls, a top plate detachably secured to said reservoir, a plurality of upstanding tubular members mounted in the floor of said reservoir and extending upwardly adjacent the top thereof, the lower end of each of said tubular members having a discharge opening therein, a valve for each of said discharge openings, a valve stem mounted within said tubular member for each of said valves, the upper end of said valve stem projecting beyond the upper end of said tubular member, a cap secured to the top end of each of said valve stems, an upwardly facing cup mounted on the top end of each of said tubular members, a compression spring bearing between said cap and cup on each of said tubular members for normally holding said valves in closed position, a unitary plate carried by said detachable cover and arranged to contact with all of said valve stem caps, a stud mounted on the said plate and extending upwardly through the opening in said cover and a cam lever mounted on the top side of said cover for forcing said stud and plate downwardly so as to open all of the valves in said oiler in unison.

4. An oiler comprising a reservoir adapted to contain oil, an upstanding tubular member mounted in the floor of said reservoir and communicating with the interior thereof, the lower end of said tubular member being provided with a discharge opening, a valve for controlling the flow of oil through said opening, a valve stem mounted within said tubular member for controlling said valve, the upper end of said valve stem projecting above the top end of said tubular member, a cap mounted on the top end of said valve stem, resilient compression means bearing between the under side of said cap and the top end of said tubular member for normally holding said valve in a closed position, manually operable means mounted on said reser-

voir for pressing down on said cap to open said discharge valve, and a wick disposed in said reservoir and partially within said tubular member, comprising an outer layer of 5 absorbent material for conducting oil from said reservoir to the discharge opening and an inner rigid core for reinforcing the same, the core being extended in advance of the outer coating.

10 Signed at Chicago this 2nd day of April, 1927.
